UNITED STATES PATENT OFFICE.

CHARLES LEDERER, OF CHICAGO, ILLINOIS.

EDUCATIONAL GAME.

Application filed March 6, 1922. Serial No. 541,529.

To all whom it may concern:

Be it known that I, CHARLES LEDERER, a citizen of the United States of America, and a resident of Chicago, county of Cook, 5 and State of Illinois, have invented a new and useful Improvement in Educational Games, of which the following is a specification.

This invention relates to educational 10 games and especially to that class of games which includes pictorial devices of sectional character adapted for interchangeable combination and arrangement in various ways to produce different pictorial effects.

15 The main objects of the invention are to provide an educational device or game of the character described comprising a plurality of fundamentally similar sectional units, the mutually corresponding parts of 20 which may be interchangeable to produce various pictorial results; to provide a series or combination of elemental card sections or blocks, each provided with a definite part of a picture, each section having one 25 or more letters whereby words may be spelled according to the specific arrangement of the elements or cards to form a picture; to provide one or more cards or 30 sections in each pictorial set adapted for use in either of two relative positions; and to provide such letters on the several sections as to facilitate the spelling of a large 35 number of words in accordance with the many possible pictorial arrangements.

35 In the illustrative embodiment shown in the drawings, Figures 1, 2 and 3 each show a comic figure of a man on the face of a sectional card.

Fig. 4 is a reverse view of one of the 40 sectional cards, all of which are alike on the back side.

Fig. 5 is a pile of card sections shuffled and ready for distribution to the players, each of whom draws a set of numerals 1 45 to 4.

Fig. 6 shows two views, 1 and 2, of the same head section mutually inverted or turned upside down relative to each other.

Fig. 7 shows a modified embodiment 50 wherein the picture sections and corresponding letters are shown on the sides of a block of cubical form.

Fig. 8 shows a list of words.

Referring to Figure 1, the card is made 55 in four separate sections, extending cross-wise of the body, the abutting edges fitting

together on the lines *a*, *b*, and *c*. The top section represents a head-covering or upper part of the head; the second section represents an invertible face; the third section 60 represents a body and arms; and the fourth section represents the legs and feet. The division lines or cuts are represented by the letters *a*, *b* and *c*.

The sectional cards shown in Figures 2 65 and 3 are structurally similar and differ only as to the appearance and detail of the character or figure represented. In each instance the character or person shown is preferably of humorous or comic nature so 70 as to add mirth to the mechanical and educational interest in the game, which is designed especially for children.

The serial designations here represented on the back enable the players to pick out 75 each a definite set adapted to fit together to make a complete picture, it being understood that the several parts of the picture are interchangeable with corresponding parts of other pictures so that the body of 80 a policeman, for instance, may be attached to the legs of a clown and to the head of a man with a tall hat.

In the case of blocks such as shown in Fig. 7 one face may be left blank for the 85 reception of a serial number, corresponding with the numbers on the backs of the card sections.

The game is used as follows: Each person, say three as for three sectional cards, 90 draws any four card sections numbered to represent a set, as shown by Figures 4 and 5. These cards are then turned over and arranged in order to form a picture. The head section may be placed either side up, 95 as may be necessary to obtain a word. In case no word results the holder scores no point. If he can obtain a word with the head in one position only he scores one point. If he gets a word for each position 100 of the head he scores two points. The cards are then shuffled and drawn again, and so on until say ten draws have been played. The scores are then counted up and the high 105 number wins the game.

In order to enhance the educational facilities and value of the game I provide with each game a list of all of the many words that may be obtained by the various proper pictorial combinations (see Fig. 8). Various lists may be compiled for various sets of letters or for different sets of cards, so 110

that the games may be made progressive, that is to say, a small set of two or three cards with a small set of simple words may be given a small child or beginner, and a larger set of cards with more words or rarer words may be used by an older child.

It is to be understood that for the purpose of the claims the word section or card may include not only a thin flat backing or sheet but also a thick member or "block" such as shown by Fig. 7.

Although but two specific embodiments of this invention are herein shown and described, it is to be understood that some of the details of the constructions and pictures shown may be altered or omitted without departing from the spirit of this invention as defined by the following claims.

I claim:

- 20 1. An educational game device comprising a plurality of sectional cards of pictorial design, the several separable sections of which are characterized by letters affixed thereto, the sections of one card being interchangeable with the corresponding sections respectively of another card to produce different pictorial designs and also different words.
- 25 2. An educational game device comprising a plurality of structurally similar sectional cards, the several separable sections of which

are indicated by letters which are normally arranged to produce a word characterizing each card respectively, the sections being interchangeable with corresponding sections respectively of different cards, whereby different pictorial designs may be produced and different words may also be produced, according to the pictures produced.

3. An educational game device comprising a plurality of sectional cards, each having a pictorial design including a head section adapted for inversion to produce a variation in pictorial effect, and each section having a letter on its front side and a numeral on its back side, the head section being provided with two mutually inverted different letters.

4. An educational game device comprising a plurality of sectional cards, each having a pictorial design including a face section adapted for inversion to produce a variation in pictorial effect, and each section having a letter on its front side and a numeral on its back side, the head section being provided with an extra letter for use when the section is inverted, the sections being numbered serially.

Signed at Chicago this 1st day of March, 1922.

CHARLES LEDERER.
